UNITED STATES PATENT OFFICE.

JOHN H. WOODBERRY, OF THE UNITED STATES ARMY.

BASE FUSE.

Application filed September 20, 1919. Serial No. 325,277.

(FILED UNDER THE ACT OF MARCH 3, 1883, 22 STAT. L., 625.)

To all whom it may concern:

Be it known that I, JOHN H. WOODBERRY, lieutenant colonel, United States Army, a citizen of the United States, stationed at 5 Washington, District of Columbia, have invented an Improvement in Base Fuses, of which the following is a specification.

The invention described herein may be used by the Government, or any of its officers or employees in prosecution of work for 10 the Government, or by any other person in the United States, without payment of any royalty thereon.

The object of my invention is, in general, 15 to provide an improved base detonating fuse, of the selective mechanical delay type, i. e., a fuse the action of which affords, through mechanical means, an automatic selective delay in firing, the delay, in all 20 cases, being proportional to the duration of the resistance to penetration encountered by the projectile, upon impact.

More specifically, the object is to provide 25 a fuse, having a normally restrained and unarmed firing pin, embodying novel means for arming the firing pin.

Another specific object is to provide a 30 detonator and primer-carrier movable, upon impact of the projectile, toward the firing pin, and embodying novel means for locking the same at the limit of such movement.

With these objects in view, the invention resides, generally stated, in a base-detonating 35 fuse embodying a normally restrained and unarmed firing pin, and means for arming the firing pin, comprising centrifugally-movable spring members co-operating with locking means for holding the firing-pin in restrained position, with its driving-spring compressed.

The invention resides, further, in a detonator and primer carrier, comprising a plunger movable, upon impact of the projectile, toward the firing-pin, and provided with a 45 rim, which is deformable or crushable, upon impact with a stationary member limiting the travel of the plunger, into a locking recess, whereby the plunger is locked against recoil.

The invention resides, finally, in certain 50 refinements of structure going to make up the ultimate perfection of the fuse, as an entirety.

The invention is graphically shown in the

accompanying drawings, which disclose an 55 exemplary embodiment capable of carrying out the underlying principles of the invention. Like reference characters designate corresponding parts throughout the several views. Briefly described:

Figure 1 is a central, longitudinal section 60 through the fuse of my invention, showing the normal position of the parts thereof;

Figure 2 is a similar view, showing the 65 position of the parts after impact of the projectile carrying the fuse;

Figure 3 is a development of the arming casing;

Figure 4 is a view in section of said 70 casing;

Figure 5 is a view in side elevation of the 75 firing-pin support.

Referring, now, in detail, to the drawings:

1 designates the fuse-stock preferably provided with a circumferential base-flange 2, and exteriorly threaded portion 3 adjacent said flange, an interiorly threaded portion 4 at the nose end, and a centrally apertured diaphragm 5 at a point between the longitudinal center of the stock and the base thereof. The space between the diaphragm 5 and the threaded plug 9 closing the base of the stock constitutes a safety chamber 6. The side 7 of said diaphragm facing the safety chamber is preferably substantially conoidal, as shown. Preferably, the wall of the safety-chamber 6 is weakened by a circumferential groove 8, affording frangibility.

Rectilinearly movable in the central aperture of the diaphragm 5 is a detonator carrier 11, which, as shown, is an elongated body of cross sectional area substantially the same as that of the central opening of the diaphragm 5, and having, at its forward 90 end, a head 12 and, at its rear, a pocket or cavity for the reception of the detonator 13. The thin end of the carrier is crimped over the detonator, forming a marginal flange 14, which holds the detonator in position.

The carrier head 12 is recessed for the 95 reception of the primer 15, and the carrier is longitudinally bored, as shown at 16, affording a flash passage from the primer to the detonator.

Preferably, a sleeve or bushing 23 encircles the carrier 11, and the forward end of the sleeve is crimped over to provide an an-

nular flange 24 seated against the inner surface of an inward-projecting, circumferential flange 25 laterally carried by a tubular member 26, provided, at its opposite end, 5 with a marginal, outward-projecting flange 27 peripherally threaded, as shown, so that the member 26 may be threaded into the threaded portion 4 of the stock 1, as clearly shown in Fig. 1. The member 26 functions 10 as a support for the detonator-carrier 11, and, also, as a guard to prevent the flame of the primer 15 reaching the booster-charge 28, should the primer be accidentally fired while the parts are in the normal position 15 shown in Fig. 1.

As shown in Fig. 1, the head 12 of the detonator-carrier 11 moves in the tubular member 26, and is approximately of the same cross sectional area as the chamber 29 20 in which it moves.

In the normal position of the detonator-carrier 11, as shown in Fig. 1, the rear end carrying the detonator 13 projects into the safety-chamber 6, the carrier being normally retained in this position by suitable mechanical means, in this instance by centrifugally-operable locking bolts 17, any suitable number of which may be employed, equidistantly spaced, and housed in radial 30 openings 18 in the diaphragm 5. The inner ends of the locking bolts are normally projected into peripheral notches 19 in the carrier 11 by coiled springs 20 bearing against the outer ends of the bolts and against disks 35 21 secured in the enlarged outer ends 22 of the openings 18. The function and operation of these centrifugal locking bolts 17 are well understood in the art, and will not be dwelt upon herein.

40 The carrier-head 12 is provided, at its free end, with a deformable locking-rim 30, which, when the carrier 11 is driven forward and strikes against a head 35, is crushed or deformed or upset into a counter-bore or recess 32 in the forward end of the tubular carrier-support 26, thus locking the carrier against recoil.

Seated in the forward end of the stock 1 is a tubular bushing or housing 33 provided 50 with an exteriorly threaded portion 34, by which the bushing may be screwed into the stock. The housing 33 is provided, at one end, with an outward-projecting, marginal flange 36, which, when the bushing is 55 screwed "home" in the stock 1, bears against the outer end thereof, as shown in Fig. 1. The bushing is also provided with an internally-threaded portion 37, at the flange end thereof, for engagement with the threaded 60 portion or a closure-plug 38.

The firing pin comprises the shank 39 terminating, at one end, in the tapering pointed portion 40, and an integral collar 41 carrying a diametric peg 42 projecting, 65 at both ends, beyond the periphery of the

firing-pin shank, for the purpose presently appearing. The firing-pin, collar, and peg may be made integral, i. e., the collar be provided with integral lugs or projections, corresponding to the projecting ends of the peg 42.

The firing pin is reciprocable in a support 43, which, as shown, is a tubular member provided, at one end, with an outward-projecting marginal flange 35, which, in the 75 assembled position of the parts, is seated against the flange 27 of the carrier support 26, and is disposed between such flange 27 and the inner end of the bushing 33.

The firing-pin support 43 is provided 80 with the longitudinally-extending, diametrically oppositely disposed, slots 44, 44, of differing lengths. Intermediate the ends thereof one of the slots is provided with an offset portion or branch 45 one of the side walls 46 thereof being inclined or oblique to the slot 44, as clearly shown in Fig. 4, for the purpose presently appearing. The other slot has a lateral offset or branch 45.

Encircling the shank 39 of the firing-pin is a coiled spring 47, one end thereof bearing against the firing-pin collar 41 and the other end against a cup 49, in which the forward portion of the firing pin support 43 is 95 seated. Between said cup and the screw closure plug 38 is a lead washer 49', to take up the recoil of the firing-pin.

The firing-pin driving spring 47 is normally under compression, and is prevented 100 from propelling the firing-pin rearward by having the projecting ends of the peg 42 seated in the offset portions 45 of the slots 44, and retained in this position by the following means:

A locking-sleeve 50 encircles and is longitudinally movable on the firing-pin support 43. Disposed interiorly of the sleeve 50 is a locking-dog 52 provided with a stem 51 extending transversely through the wall of the sleeve, whereby the locking dog is secured to and is thus carried by the sleeve 50. The locking-dog is seated and reciprocates in that slot 44 which has the greater length. Normally, the locking dog 52 is disposed in 115 the path of movement of the peg 42 from the offset portion 45 of the slot 44 and blocks passage of the peg from such offset portion to said slot, as shown in Fig. 1.

The locking sleeve 50 may be provided with a sloping exterior surface 53, terminating, at one end, at a shoulder 58 encircling the sleeve.

Centrifugally-operable means are provided for normally maintaining the locking sleeve 50 with the locking-dog 52 in locking position, as shown in Fig. 1, and I have shown in the drawings my preferred means, which I will now describe:

Disposed between the inner end of the 130

plug 38 and the tubular bushing 33 is a metallic arming casing, which, as shown, is a ring or band 56 carrying a series of equidistantly spaced, spring fingers 57, bent or inclined so as to converge at their free ends, as shown in the drawings. The inclined spring fingers bear against the inclined surface 53 of the locking sleeve 50, and the free ends thereof bear against the shoulder 58, thus preventing longitudinal movement of the sleeve 50 in a direction to release the firing-pin.

Preferably, at least one of the spring fingers 57 is crimped, on the arc of a circle, as shown at 59, at a point adjacent the ring 56, forming what may be termed a hump, which normally enters the space between the adjacent ends of the locking-sleeve 50 and the plug 38.

Advantageously, the spring fingers 57 and the ring 56 are formed integral, as by being stamped out of a blank of spring metal, and bent up to form.

While the operation of the fuse is, probably, apparent from the foregoing description of the construction and the relation of the parts, it may be briefly explained as follows:

The normal position of the parts is as shown in Fig. 1, wherein the detonator-carrier 11 is locked against movement by the locking bolts 17, and wherein the firing-pin driving spring 47 is compressed and the firing-pin turned so that the projecting ends of the peg 42 are seated in the offset portions or branches 45 of the slots 44, 44, and retained therein by the locking-dog 52 carried by the locking-sleeve 50. During flight, when the centrifugal force acting on the locking-bolts 17 overcomes the inertia thereof, i. e., when positive linear acceleration ceases, they move radially outward, thus releasing the detonator-carrier 11.

Also, when centrifugal force acting on the spring fingers 57 becomes sufficiently great, they flex outward, releasing the locking-sleeve 50 and arming the firing-pin.

Upon impact, the projectile and fuse are retarded throughout the duration of the resistance encountered. The tendency of all parts on the interior of the fuse is to move forward through the force due to inertia of these parts. The carrier 11, therefore, drives forward against the head 35, crushing the rim 30 into the counterbore 31, thereby locking the carrier against recoil. The locking sleeve 50, being no longer prevented from moving forward, also slides forward against the inner end of the plug 38, the locking-dog 52 moving with the sleeve so as to uncover the offset portion 45 in which the corresponding projecting end of the peg 42 is seated. As the sleeve 50 drives forward, it brushes by the offset portion 59, flexing the same outward. As will be understood, the

hump 59 functions as a safety-means to prevent premature movement of the sleeve 50 after the spring fingers, under centrifugal force, release the sleeve.

So long as the resistance is such as to cause the inertia of the firing pin and spring to produce a force greater than and counter to the force of the spring 47, the firing pin spring remains compressed. When the resistance becomes insufficient to keep the firing-pin spring compressed, the spring extends itself with a force equal to the difference between the force due to the inertia of these parts and the force of the spring. If the cessation is sufficiently sudden, the firing-pin will be projected into the primer 15 with sufficient force to explode the same. If, however, the resistance should cease gradually, the firing-pin spring would also extend gradually and, consequently, the firing-pin, moving thus slowly under the influence of the slowly expanding spring, would not have sufficient force to fire the primer. To obviate such an occurrence, means are provided for retarding the extension of the spring until sufficient force is accumulated therein to fire the primer when the spring extends. This retardation of action of the spring is accomplished by cutting the inclined wall 46 of the branches 45, in which the projecting ends of the peg 42 rests, at such an angle to the slots 44 that it will require a force sufficiently great to fire the primer, to overcome friction between the peg ends and said offset portions and drive the projecting ends of the peg into the longitudinal slots 44, 44. It will thus be seen that a gradual cessation of resistance to penetration will not cause the spring 47 to extend gradually, but with sufficient force, in all cases, to fire the primer. The projecting ends of the peg 42 rotate out of the branches 45 and then, with a longitudinal movement, the firing pin is propelled, under the action of its driving spring, against the primer.

The action of the fuse gives an automatic selective delay in firing, through mechanical means, the delay, in all cases, being proportional to the resistance encountered.

Having thus fully described my invention, what I claim as new and desire to secure by Letters Patent is:—

1. In a fuse, the combination, with a normally-restrained firing pin carrying a radial projection and releasable by an axial turning movement, of a casing in which said firing pin reciprocates and having a longitudinally-extending slot in which the firing-pin projection moves when the firing-pin reciprocates, said slot being provided with an offset portion in which said projection normally rests, a locking-dog reciprocable in said slot and normally holding said projection in said offset portion of the slot, and means for normally holding said dog in such opera-

tive locking position, including centrifugally-movable spring locking members.

2. In a fuse, the combination, with a normally-restrained firing pin carrying a radial projection and releasable by an axial turning movement, of a casing in which said firing pin reciprocates and having a longitudinally-extending slot in which the firing-pin projection moves when the firing-pin reciprocates, said slot being provided with an offset portion in which said projection normally rests, a locking-dog reciprocable in said slot and normally holding said projection in said offset portion of the slot, a locking-sleeve encircling said casing and carrying said locking-dog, and centrifugally-movable spring members normally preventing movement of said locking-sleeve.

3. In a fuse, the combination, with a normally-restrained firing pin carrying a radial projection and releasable by an axial turning movement, of a casing in which said firing pin reciprocates and having a longitudinally-extending slot in which the firing-pin projection moves when the firing-pin reciprocates, said slot being provided with an off-set portion in which said projection normally rests, a locking-dog reciprocable in said slot and normally holding said projection in said offset portion of the slot, a locking-sleeve encircling said casing and carrying said locking-dog, and a member carrying centrifugally-movable spring fingers normally resting upon said locking-sleeve and preventing movement thereof.

4. In a fuse, the combination, with a normally-restrained firing pin carrying a radial projection and releasable by an axial turning movement, of a casing in which said firing pin reciprocates and having a longitudinally-extending slot in which the firing-pin projection moves when the firing pin reciprocates, said slot being provided with an offset portion in which said projection normally rests, a locking-dog reciprocable in said slot and normally holding said projection in said offset portion of the slot, a locking-sleeve encircling said casing and carrying said locking-dog, and centrifugally-movable leaf-springs normally bearing against said locking-sleeve and preventing movement thereof.

5. In a fuse, the combination, with a normally-restrained firing pin carrying a radial projection and releasable by an axial turning movement, of a casing in which said firing pin reciprocates, and having a longitudinally-extending slot in which the firing pin projection moves when the firing pin reciprocates, said slot being provided with an offset portion in which said projection normally rests, a locking-dog reciprocable in said slot and normally holding said projection in said offset portion of the slot, a locking-sleeve encircling said casing and carry-

ing said locking-dog, and an annular member carrying a circularly-arranged series of spring fingers normally bearing upon said locking-sleeve and preventing movement thereof.

6. In a fuse, the combination, with a normally-restrained firing pin carrying a radial projection and releasable by an axial turning movement, of a casing in which said firing pin reciprocates, and having a longitudinally-extending slot in which the firing pin projection moves when the firing pin reciprocates, said slot being provided with an offset portion in which said projection normally rests, a locking-dog reciprocable in said slot and normally holding said projection in said offset portion of the slot, a locking-sleeve encircling said casing and carrying said locking-dog and provided with an inclined exterior surface, and centrifugally-movable leaf-springs normally bearing against said inclined surface and preventing movement of said locking-sleeve.

7. In a fuse, the combination, with a normally-restrained firing pin carrying a radial projection and releasable by an axial turning movement, of a casing in which said firing pin reciprocates, and having a longitudinally-extending slot in which the firing-pin projection moves when the firing pin reciprocates, said slot being provided with an offset portion in which said projection normally rests, a locking-dog reciprocable in said slot and normally holding said projection in said offset portion of the slot, a locking-sleeve encircling said casing and carrying said locking-dog and provided with an annular circumferential shoulder, and centrifugally-movable leaf-springs normally bearing against said shoulder and preventing movement of said locking-sleeve.

8. In a fuse, the combination, with a normally-restrained firing pin carrying a radial projection and releasable by an axial turning movement, of a casing in which said firing pin reciprocates, and having a longitudinally-extending slot in which the firing pin projection moves when the firing pin reciprocates, said slot being provided with an offset portion in which said projection normally rests, a locking-dog reciprocable in said slot and normally holding said projection in said offset portion of the slot, a locking-sleeve encircling said casing and carrying said locking-dog and provided with an annular circumferential shoulder, and centrifugally-movable leaf-springs normally bearing against said shoulder and preventing movement of said locking-sleeve, one of said leaf-springs being crimped to provide an offset portion normally bearing against one end of said locking-sleeve.

9. In a fuse, the combination, with the firing pin, of the driving spring therefor, means for normally maintaining said firing

- pin in unarmed position, with its spring compressed, including a movable locking member and centrifugally-movable locking springs normally co-operating with said locking member, and means carried by one of said springs for yieldingly holding said locking member against movement after release thereof by said springs under centrifugal force.
10. In a fuse, the combination, with the firing pin, of the driving spring therefor, means for normally maintaining said firing pin in unarmed position, with its spring compressed, including a movable locking member and centrifugally-movable locking springs normally co-operating with said locking member, and a flexible projection carried by one of said springs and normally bearing against said locking member for yieldingly holding it against movement after release thereof by said springs under centrifugal force.
11. A fuse provided with a rectilinearly-movable primer-carrying plunger carrying means deformable for locking the same near the limit of its travel.
12. A fuse provided with a rectilinearly-movable primer-carrying plunger carrying a member at one end thereof deformable for locking the same near the limit of its travel.
13. A fuse provided with a rectilinearly-movable primer-carrying plunger carrying a deformable rim at one end thereof for locking the same near the limit of its travel.
14. A fuse provided internally with a locking recess and with a stationary impact-member adjacent thereto, and a rectilinearly-movable primer-carrying plunger having means deformable into said locking recess upon impact of said plunger with said impact-member.
15. In a fuse, a firing-pin, a primer-carrying plunger movable toward said firing pin, and means carried by said plunger deformable for locking the plunger after movement toward said firing pin.

JOHN H. WOODBERRY.
